UNITED STATES PATENT OFFICE.

WILLIAM H. ZINN, OF NEW YORK, N. Y.

DESIGN FOR A BAGGAGE-STAND.

SPECIFICATION forming part of Design No. 27,227, dated June 15, 1897.

Application filed May 8, 1897. Serial No. 635,740. Term of patent 7 years.

To all whom it may concern:

Be it known that I, WILLIAM H. ZINN, of New York, in the county of New York and State of New York, have invented and produced a certain new and original Design for a Baggage-Stand, of which the following is a specification.

Reference is to be had to the accompanying drawings, forming a part of this application, which show my design for a baggage-stand.

Figure 1 is a perspective view showing my design. Fig. 2 shows a side elevation thereof. Fig. 3 shows an end elevation thereof.

The leading or material feature of my design consists in a ladder-shaped device *a*, resting upon four columns or supports *b*, connected intermediate of their ends by members *f*, the ends of the ladder-shaped device *a* projecting beyond the points where this device rests upon the columns *b*.

As shown in the drawings, the ladder-

shaped device *a* is composed of two symmetrically-shaped pieces *a'*, connected by complementary pieces *a''*. The supports or columns *b* are shown four in number, arranged in complementary vertical planes, upon the upper ends of which rests the ladder-shaped device arranged in a horizontal plane. The members *f* are substantially in a plane parallel with that of the ladder-shaped devices. 30

I claim—

The design for a baggage-stand, substantially as shown and described.

In testimony whereof I have signed my name to this specification, in the presence of 35 two subscribing witnesses, this 5th day of May, A. D. 1897.

WILLIAM H. ZINN.
